UNITED STATES PATENT OFFICE.

NELSON LEWIS TUCK, OF PHILADELPHIA, PENNSYLVANIA.

MACHINE FOR PRINTING OIL-CLOTH.

SPECIFICATION forming part of Letters Patent No. 377,789, dated February 14, 1888.

Application filed April 25, 1887. Serial No. 235,982. (No model.)

To all whom it may concern:

Be it known that I, NELSON LEWIS TUCK, a citizen of the United States, formerly of Chicopee, Massachusetts, but now residing at Philadelphia, in the county of Philadelphia, and State of Pennsylvania, have invented certain new and useful Improvements in Block Printing Machines for Printing Oil Cloths and other Fabrics, of which the following is a specification.

Nature and objects of the invention.—The object of my invention is the construction of a simple, durable, and easily operated machine for printing, with rapidity and precision, in one or more colors, such prepared fabrics as constitute the body or foundation web of floor and other oil cloths.

Broadly stated, my invention comprehends the combination, in an automatic machine, possessing a fixed bed upon which the fabric to be printed is laid and along which it is caused to travel, of the following co-operating instrumentalities:—first, an intermittently operating fabric-feed adapted to intermittently act upon the fabric to be printed, and advance it along the printing bed; second, feed-operating mechanism for first advancing the feed engaged with the fabric a predetermined distance, and for then occasioning the retreat of said feed disengaged from said fabric; third, a series of tumbling, oscillatory, or reciprocating reversing, block carriers, equipped each as to its printing face with any preferred form of printing block; fourth, block-carrier-actuating mechanism adapted to alternately occasion the simultaneous descent of the block carriers upon the fabric on the bed, and the simultaneous reversal and ascent of said block carriers from the bed against color-supplying devices supported above the bed; fifth, color-supplying devices supported above the bed and adapted to supply color to the printing blocks; and, sixth, suitable mechanism for occasioning the concomitant and associated operation of the feed-operating and the block-carrier-actuating mechanisms.

My invention further comprehends the provision of means for maintaining the web of fabric taut or under tension upon the bed;—the provision of means for retaining said fabric in its advanced position against possible retreat;—the provision of suitable means for so

timing the respective movements of the fabric-feed and the block-carriers that the feed ceases to act to advance the fabric an instant before the block-carriers descend upon the fabric so advanced;—the construction of a special color-supplying device, one for each block carrier employed, embodying an intermittently-operated endless apron combined with a tank, trough, or other receptacle to contain paint, and provided with an elastic or resilient surface to cushion the printing block when applied against it, and with a doctor for removing the surplus paint from the apron after its passage through the trough and before its presentation upon said elastic bed, and further supplied with suitable means for occasioning the intermittent travel of the apron during the interval when the printing block has left its surface to descend upon the fabric to be printed;—and the construction of a special intermittently-operating fabric-feed for acting upon one or both margins of the fabric along such part of its extent as is for the time being beneath the block-carriers.

Machinery embodying my invention in a practical form is represented in the accompanying drawings and described in this specification, the particular subject-matter claimed as novel being hereinafter definitely specified.

Description of the Drawings.—In the drawings, Figure 1 is a side elevation of a machine embodying my improvements, the block-carriers being represented down upon the bed and the feed in its advanced position. Fig. 2 is a longitudinal, vertical, sectional elevation through the said machine represented in Fig. 1, in the plane of the dotted line 11 of Fig. 3 and sight being taken in the direction of the arrows upon said line,—the block-carriers being represented up against the color-supplying aprons, and the feed in its retreated position. Fig. 3 is a right hand end elevational view of the machine represented in Fig. 1. Fig. 4 is a left hand end elevational view of the machine represented in Fig. 1. In Fig. 3 the block-carriers are up against the color-supplying aprons, while in Fig. 4 they are down upon the bed. Fig. 5 is a transverse, sectional, elevation through the machine represented in Fig. 1 in the plane of the dotted line 22 of said Fig. 1, and sight being taken in the direction of the arrows upon said line. Fig. 6 is a transverse, sec-

tional, fragmentary elevation through a portion of the machine of Fig. 1 in planes of the dotted line 3 3 of said Fig. 1, and sight being taken in the direction of the arrows upon said line. The view is especially designed to illustrate the feed cam, the feed levers, and the transverse yoke between said levers. Fig. 7 is a fragmentary perspective detail of a portion of the main shaft, one of the bevel spur 10 wheels upon said shaft, and the lever for shifting said spur wheel. Fig. 8 is a side elevational view of a color-feed device which I prefer to employ. Fig. 9 is a left hand end elevational view of the color-feed device of 15 Fig. 8. Fig. 10 is a longitudinal, vertical, sectional elevation through the bottom board, pad board, and pad, of said color-feed device of Figs. 8 and 9. Fig. 11 is a fragmentary side elevational detail of a portion of one of 20 the pairs of fabric feed bars, in the position which said bars occupy when their connecting links are straightened and the bars apart to the limit of their separation. Fig. 12 is a top plan view of a portion of one of the under 25 feed bars of a given pair of bars. Fig. 13 is a transverse sectional elevation through the bars of a pair of feed bars and through one of their connecting links. Fig. 14 is a fragmentary, transverse, sectional detail through a portion 30 of the bed and one of the slotted standards, showing the application of the under bar of a pair of fabric feed bars, shown in section, to its grooved way in the bed. Fig. 15 is a fragmentary side elevational view of a portion of one of 35 one of the standards and of one of the pitman couplings by which the pitmen are connected with the block-carrier pivot pins. Fig. 16 is a top plan view of the devices represented in Fig. 15, the standard being horizontally sectioned in the plane of the dotted line 4 4 of 40 said Fig. 15. Fig. 17 is a fragmentary plan of the feed cam, driven pinion, and main shaft, and of the back gear for throwing said feed cam into or out of operation. Fig. 18 is a 45 magnified side elevational detail of one of the slotted standards and a portion of the framework, representing as applied thereto and down upon the bed a modified form of block-carrier which can be employed as a substitute 50 for the block carriers represented in the other figures of the drawings. Fig. 19 is a fragmentary partly sectional and partly elevational view of a clutch device which may be employed as a substitute for the sprocket chain 55 device represented in Figs. 1 to 5, for actuating the driving roller of the color feed apron. Similar letters of reference indicate corresponding parts.

The frame-work.—The frame-work is of any 60 preferred character, and is conveniently composed of side frames, which are designated by the letter A, and of a level bed a supported in a horizontal plane between said side frames. B are a series of slotted standards, vertically 65 erected in consecutive opposite pairs from the respective side frames and forming a fixed portion of the frame-work.

The frame-work as an entirety may be mounted upon pillow blocks or pedestals, or, as is desirable in oil cloth manufacture, upon 70 rollers or trucks so that the machine may be readily moved. The bed may be made of any desired width, conveniently that of a standard oil cloth fabric. Upon the feeding end of the bed is mounted a tension or pressure roller 75 C, under which the fabric fed upon the bed of the machine is caused to travel. The guides c of this roller are journaled in boxings c^x free for vertical movement in slotted roller-standards c² erected at each side of the bed. 80 This construction permits the roller to ride over fabrics of different thicknesses.

The fabric feed.—The fabric feed device which I prefer to employ is a draft or traction device composed of two pairs of parallel-bar 85 clamps, each pair preferably of about the length of the bed, and one applied at each side of said bed. Each of these clamps is composed of two feed bars D D^x connected together by links d, pivoted, within recesses 90 therein, to the respective bars, so that the latter are connected after the well known manner of the two members of a parallel ruler. The length of the bar-connecting links is such that when said links are straightened 95 and the bars in consequence apart the full limit of their separation, as shown in Fig. 11, the distance between the opposing faces of the bars is greater than the thickness of the thickest fabric intended to be fed.

The under face of the upper bar D is preferably provided with teeth, as shown, or is notched, serrated, or roughened in any preferred manner. If desired, the upper face of the under bar D^x may be similarly toothed or 105 roughened. Each of the under bars of each pair of feed bars, is conveniently provided with lateral basal flanges d^x, and the under bar of each pair is thereby adapted to be seated within longitudinally extending grooved ways 110 a^x, Figs. 3, 4, 5, 6 and 14, formed along the lateral edges of the bed in such manner that when the aforesaid under bars are within the aforesaid ways the upper faces of said bars are flush with the carrying level or face of the 115 bed.

d^x, Fig. 14, is a guard, a series of which are applied to the standards to retain the upper feed bars in proper position during their longitudinal movement.

Assuming the machine to be constructed for the printing of a web of fabric of some standard width, the breadth of the bed is such that the edges of the fabric traveling over said bed extend on each side between the respective 125 feed bars of each pair of feed bars. Traction simultaneously exerted, in the direction of the intended travel of the web upon the bed, upon the two upper feed bars D of each pair, will, as is manifest, occasion a forward deflection 130 of the bar-connecting links and the descent of each upper feed bar toward the under feed bar with which it is connected and upon that edge of the fabric which, for the time being, is be-

tween the bars of each pair, so as to occasion the gripping of such edge between each pair of bars. Continued traction similarly applied will occasion the advance of each pair of feed bars compressed together, or in grip upon the fabric, through their grooved ways, and with them of the said fabric, a distance equal to the advance movement of said bars. A reverse thrust simultaneously applied to the two upper feed bars will occasion the straightening of the links until, for convenience, they encounter shoulders d^2 formed upon the feed bars, and are thereby maintained at right angles to the bars, having, of course, released their grip upon the fabric, in which position a continuance of said reverse thrust will cause the retreat of each pair of bars in release upon the fabric to their normal position, the fabric remaining in its advanced position.

20 *The feed-actuating devices.*—The specific means by which this intermittent advance and retreat of the fabric feed bars represented is occasioned is not of importance,—and many devices can be employed for the purpose. I have found a suitable contrivance to be the following.

E is a driving shaft suitably housed, conveniently in hangers e , centrally beneath the bed and extending in the direction of the length of the machine. This shaft is adapted to be driven by one or more pulleys E^x , and near the delivery end of the machine is provided with a fixed driven pinion e^2 , and adjacent to said pinion with a loosely applied or 30 rotatable feed cam F, fixedly provided with a cam spur wheel F^x by means of which said feed cam is rotated. The cam is circumscribed by a continuous cam groove f of suitable curvature to occasion, as hereinafter explained, the 35 oscillation of a pair of feed levers H.

G is a counter shaft suspended in hangers g in parallelism with the driving shaft and, as shown, slightly above and to the left hand of said shaft. Upon the countershaft is mounted 40 an eccentric hub or sleeve g^x , Fig. 17, of the length of the feed cam, and said sleeve is at its outer extremity formed or fixedly provided with a sleeve pinion g^2 which faces and is adapted to engage with the teeth of the cam 45 spur wheel F^x , and at its inner extremity formed or fixedly provided with a sleeve spur wheel g^3 which faces and is adapted to be engaged with the teeth of the driven pinion e^2 . The eccentric sleeve, sleeve, pinion, and sleeve 50 spur wheel, being a connected whole, are adapted for eccentric movement with or upon the counter shaft G as an axis, and said counter shaft is so disposed relatively to the driving shaft that the sleeve pinion g^2 and sleeve 55 spur wheel g^3 can, at will, be engaged with or disengaged from the cam spur wheel F^x and the driven pinion e^2 , and so disposed also that when engaged they will remain in engagement.

60 g^4 is a handle, conveniently connected with the sleeve pinion, by the aid of which the eccentric movement described can be imparted to said sleeve pinion and spur wheel.

As will be apparent, this device, which is in the nature of a back gear to a lathe, has for its object simply the rotation or the rest of the feed cam,—engagement effecting rotation and disengagement securing rest. The entire back gear device described is simply one of convenience to permit of the ready throwing out of action of the fabric-feed, when, for instance, it is desired to impart two impressions of the blocks to the same face area of the fabric to be printed, without in the interim between the impressions occasioning the advance of said fabric.

65 There are two feed levers respectively oppositely pivoted upon fulcrum pins h to the side frames of the machine, and as to their lower arms conveniently connected by a transverse yoke h^x , Fig. 6, bridging beneath the feed cam and the back gear and equipped with a cam lug h^3 , conveniently in the form of a roller, engaged in the cam groove f of the feed cam F. As will be apparent, rotation of the feed cam will occasion the forward and back oscillation of the yoke of the feed levers and with said yoke of said levers. The upper arms of the feed levers are respectively provided with internally oppositely projecting adjustable lever pins h^3 , which are respectively engaged with lever 70 housings D^2 , Figs. 1, 2 and 11, respectively applied to the upper or draft feed bars D of each pair of feed bars. These lever housings D^2 are conveniently made as vertical plates one erected from the upper surface of each upper 75 feed bar D, and each housing is conveniently internally triangularly recessed to present a reversing face d^3 against which the lever pin h^3 of the feed lever operating in connection with said housing exerts its thrust to occasion the retreat of the pair of feed bars in question; and also to present a draft face d^4 , included between the upper portion of the recess of the housing and the dotted line 5 5 of Fig. 11, against which 80 said lever pin acts to occasion the advance of said pair of feed bars, and also an idle face d^5 , included between the said line 5 5 and the bottom of the recess, against which said lever pin, as the lever completes its forward throw, runs idle without exerting any traction upon 85 the feed bars. It will now be understood that a half turn of the feed cam will occasion such a backward oscillation of the upper extremities of the feed levers as will occasion the retreat of both pair of feed bars, and that a further half turn will occasion such a forward 90 oscillation of said extremities of said levers as will occasion the advance of both pair of feed levers a predetermined distance, being the desired limit of advance of the feed bars, 95 and equal to the breadth of the printing face of a block-carrier. The final completion of said forward oscillation of said feed levers is, 100 as stated, without effect upon the feed bars.

105 As will be hereinafter explained, the driving shaft is the prime motor of the machine as represented in the drawings, and, through connected instrumentalities, occasions by its own rotation the ascent and descent of the 110

block carriers, and therefore it is that, as the feed cam is connected with and rotated by said driving shaft, there exists a necessity for the provision of some such lost motion contrivance as the idle faces of the lever housings, in order to cause the feed to cease to act an instant before the block-carriers are caused to descend upon the fabric advanced by said feed. For, without the provision of the idle faces, as the machine is organized, in as much as the feed levers do not complete their forward oscillation until the feed cam completes that half turn which occasions said advance, the fabric would be in movement by the feed even after the printing faces of the printing blocks had commenced to graze its surface and the instant before their ultimate pressure was imparted to them, with the result that the pattern would be imperfectly printed and the colors smeared. It is, of course, apparent that the necessity for the provision of the specific means above described for so timing the respective movements of the feed and the printing block-carriers that the feed ceases to act to advance the fabric. an instant before the block-carriers descend upon the fabric so advanced, can be obviated by so forming the cam groove f , or so timing the movement of the feed cam itself that it ceases its action to occasion the forward oscillation of the feed levers before the driving shaft completes its full rotation necessary as hereinafter explained to occasion the ultimate pressure of the printing block-carriers upon the fabric, and therefore obvious that the idle faces are devices of convenience.

A fabric feed such as the foregoing and made double so as to act upon both edges of the fabric to be advanced, is such a feed as I prefer to employ. It is proper for me to state, however, that other forms of fabric feeding device adapted to co operate with tumbling or reciprocating block carriers can be substituted for said feed, and also that it is quite possible, in connection with suitable tension-regulating contrivances and devices for preventing unintentional backward movement of the fabric, to provide and operate the machine in connection with a fabric feed which acts upon but one edge of the fabric,—a single pair of feed bars, such, for instance, as those described, being adapted to accomplish the feeding of said fabric.

Fabric retaining devices.—In order to prevent any possible backward movement of the fabric after it has been fed or advanced, I prefer to provide at each side of the bed near the delivery end thereof, a pivoted toe cam I , conveniently pivoted against cam standards i erected from the side frames, the said cams being each controlled by a spring i^x to maintain them constantly in bite as to their cam faces upon the upper level of the margin of the fabric. Of course these toe cams do not hinder the operation of the feed, as the form of their acting faces is such that the fabric readily slips under them in one direction, raising them and compressing their springs; the fabric, however, as the feed retreats, is by said cams, under

stress of their springs, retained against backward movement. It is of advantage to apply additional toe cams between the tension roller and the first block-carrier, but I have not considered it necessary to illustrate their application.

The block carriers.— K are the block carriers, and K^x any usual or preferred printing blocks which are removably applied and secured to the faces of said carriers in any preferred manner.

In speaking of the block-carriers, I, for greater convenience, include the blocks, which, of course, are the printing devices strictly as such, while the carriers are the devices which carry and actuate them, and in the claims I employ the term "printing-block-carriers" to include both the carrier and the printing block or printing instrumentality *per se*. As all of these block-carriers are of the same construction, employed in any desired series, and operated simultaneously and similarly by simultaneously operating and similar mechanical devices, it will be sufficient to describe the construction and mode of operation of but one of them,—it being, of course, understood that although the machine represented in the drawings employs three block-carriers, fewer or a greater number than three can be employed.

The carrier proper K , is a plate of any preferred construction and material, wide enough to extend across the breadth of any web of fabric the bed is adapted to receive, and right angularly disposed with respect to that pair of slotted standards B in connection with which it operates. Confining my description to the first seventeen figures of the drawings, the block-carrier is provided at its sides with a pair of companion or counter-part tumbler plates k , which are in the nature of wings, webs, or sides, erected, preferably at right angles to the plane of the face of the carrier, at each side thereof. Each of these tumbler plates is provided with a carrier pivot pin k^x , the said pins being in opposite alignment and being together the fulcrum or pivotal axis with respect to which the carrier proper tumbles, oscillates, partially rotates, or reverses in ascending and descending, performing a movement hereinafter referred to in the claims by the qualifying expression "reciprocating reversing." Each of these tumbler plates is also provided with a pair of tumbler pin ways k^1 k^2 , adapted in the ascent and descent of the block carriers to be respectively engaged with tumbler pins b^1 b^2 projecting internally, as shown in the drawings, from the respective slotted standards with reference to which the block carrier ascends and descends. The carrier pivot pins are conveniently of a diameter equal to the breadth of the vertical slots on the standards B so as to fill said slots, and project outwardly through their respective standards.

The block-carrier-actuating devices.—It will be apparent that when the block carrier has de-

scended and is resting level upon the fabric to be printed, as represented in Figs. 1 and 4, its tumbler pin ways k^2 will be engaged with the tumbler pins b^2 . It will also be apparent that if

5 the carrier pivot pins k^x are then caused to ascend through their slots in the slotted standards, the carrier with which they are connected will be raised from off the bed, and, by the engagement of its tumbler pins b^2 with the 10 pin ways k^2 , will be tumbled, or partly rotated, or oscillated, until its tumbler pin ways k^2 engage with the tumbler pins b^2 , and by said last named engagement will be further tumbled, partly rotated, or oscillated until it, the said 15 block-carrier, has reversed itself, in which position of reversal it will have completed its ascent. It will be also apparent that, if now the carrier pivot pins are caused to descend, the reverse action of the tumbler pins and pin 20 ways in connection with said descent of the carrier pivot pins, will occasion the reverse tumbling, partial rotation, or oscillation of the carrier until it has again reversed itself and assumed its former position upon the bed.

25 The specific means by which the ascent and descent of the block-carriers is occasioned is not of importance, and many devices may be employed for the purpose. I have found the following to be suitable contrivances for actuating the block-carriers:—Exterior to the outside faces of the standards the carrier pivot pins k^x are journaled in pitman couplings l , of any usual or preferred construction, connected with the upper extremities of carrier pitmen 30 L which at their lower extremities are boxed upon the wrist pins m of carrier cranks M respectively connected with the outer extremities of transverse crank shafts N journaled beneath the bed, the inner extremities of which 35 shafts are armed with beveled pinions n engaged with a beveled spur wheel O mounted upon and rotatable with the driving shaft.

It will be apparent that the rotation of the beveled spur wheel O with the driving shaft 45 will occasion the reverse rotation of the beveled pinions n with which it is engaged and of their crank shafts N , and the consequent reverse throw of the associated carrier cranks M and pitmen L . As, however, the engagement 50 of the beveled spur wheel with the beveled pinions is such that when the block carrier has completely descended both of the cranks of said carrier are down and lying in the same vertical plane, or in the position represented in Figs. 1, 4 and 5, it is apparent that, 55 although the cranks travel in opposite directions they will, when the block-carrier has ascended, both stand up in the same vertical plane, as shown in Fig. 3, and, that, therefore, 60 it is inconsequential that their respective rotations or throws happen to be in opposite directions.

The pitman couplings l are preferably provided with an adjusting bolt l^x , or other preferred adjusting device, by the aid of which 65 an exact adjustment of the "stroke," so to speak, of the block-carriers can be effected,

and the block-carriers caused to impinge with a greater or less pressure respectively upon the fabric on the bed and against the color-supplying devices. 70

In order readily to permit of the throwing out of action of any particular block-carrier, each beveled spur wheel O is conveniently feathered upon the driving shaft and provided 75 with a bifurcated lever O^x , Fig. 7, suitably fulcrumed and conveniently engaged with a groove in or a collar upon the hub of the spur wheel, by the throw of which lever the spur wheel with which it is connected can be slid 80 along the shaft out of engagement with the beveled pinions in connection with which it normally operates. Instead of the foregoing lever and feather contrivance, it is obvious 85 that any usual clutch contrivance may be fastened upon the shaft, and the spur wheel be adapted to be run free upon said shaft in continuous engagement with its pinions but inert to rotate them when its clutch, which is fixed upon the shaft, is out of engagement with it, 90 the said spur wheel.

Block-carrier-actuating devices of the foregoing, or of any other preferred construction, being arranged in series correspondent with the series of block-carriers, are, as is apparent, 95 organized to alternately occasion the simultaneous tumbling descent of all of the block-carriers and their simultaneous tread upon the fabric on the bed an instant after the said fabric fed forward has come to rest upon said bed, 100 and then the simultaneous tumbling ascent of said block-carriers to their color-supplying devices.

It will now be understood in what manner the driving shaft as the prime motor, and its driven feed-operating devices and carrier-actuating devices, together act in predetermined association to occasion the intermittent operation of the fabric-feed and the intermittent ascent and descent of the block carriers; and 105 it is to be further understood that the said associated operation is so timed that the fabric feed bars are retreating out of engagement with the fabric to seize the fabric for a further advance during the period when the block-carriers are ascending, and advancing with the fabric in their grip during the period when the block-carriers are descending from their color supplying devices to said fabric so fed forward to receive their impression. 110

As will be apparent by a reference to the drawings, all of the block-carriers of the series employed, when upon the fabric, are respectively disposed apart a distance exactly equal to the breadth of a carrier, and, as 115 stated, each advance of the fabric by the feed is a distance equal to the breadth of a carrier. It will therefore be understood that the imprint of each block after the first, as said blocks are successively caused to tread upon the fabric, will be made upon that surface area of said fabric which has received the impression of said first block, and that, therefore, 120 all of the blocks serve in turn to print 130

their part of a given pattern, or design to be printed, in given colors upon said fabric.

The color feed.—The gist of my invention residing in the combination in an automatic machine of an intermittently operating feed acting upon the fabric to be printed, with a series of tumbling, oscillatory, or reciprocating reversing, block carriers, and with color-supplying devices adapted to supply color to said carriers,—it is apparent that it is not of the essence of the said invention, the gist of which, as stated, resides in the combination of the three foregoing elements, in connection, of course, with suitable mechanical means for occasioning their concomitant operation, what form of color-supplying devices, broadly as such, are employed to supply color to the faces of the said printing blocks, and many forms of color-feed may, in fact, be employed. I prefer, however, to employ a series of independent color-feeds of the following novel construction, one of which operates in connection with a given block-carrier, and which in series operate with the carriers in corresponding series, and which are conveniently supported upon the slotted standards in connection with which said carrier operates. Each of these color feeds being of the same construction, I will describe but one of them, it being the fact, as stated, that a series corresponding in number with the series of block carriers is employed.

The color feed, Figs. 8, 9 and 10, consists essentially of an intermittently operated endless apron P for supplying color, preferably but not necessarily formed of a web of oil cloth or other fibrous or textile fabric, and traveling over parallel rollers, one of which p is a driving roller to which motion of rotation is at intervals imparted, and the other an idler or driven roller p^x taking its motion from the belt. The gudgeons p² of each of these rollers are respectively contained in adjustable boxes p³ mounted in a pair of connected parallel side frames Q. The said frames are adapted to be supported above the bed in any preferred manner, conveniently by being connected to the slotted standards of the frame work, and they serve to contain between them the bottom board q of a color trough combined with the apron, and what I term a pad board q^x over the under face of which is stretched a pad or web q² of felting, rubber, or other preferred material, over which the active surface of the endless apron travels after it emerges from the trough, and which serves as an elastic or resilient surface for cushioning the printing block when pressed by its ascended carrier against said apron upon said pad. The bottom board and pad board are not necessarily separate boards, but it is convenient to make them so and to connect them by bolts q³ as shown in Fig. 10. In order to permit of the ready application and removal of the pad q², the latter is conveniently stretched lengthwise along the under surface of the pad board,

turned up over both its ends, and secured upon pins q⁴ applied in recessed portions of said pad board as shown in said Fig. 10.

The pad board and bottom board, together supporting the passive surface of the apron, constitute with said apron the bottom of the trough, the sides q⁵ of which are constituted by two independent upright boards conveniently affixed to the side frames by being bolted thereto as shown in Figs. 8 and 9, and the end of which trough is constituted by a transverse doctor q⁶, adjustably connected with the extremities of the sides by means of threaded lugs q⁷ engaged with adjusting doctor bolts q⁸ threaded through bearings q⁹ fixed upon said sides of the trough. As the side frames and apron in their mounting upon or with respect to the framework of the machine have an inclination downwardly from the feeding to the delivery end of the machine, and as the apron travels in the direction of the length of the machine, it is apparent that the paint or liquid coloring matter will be contained between the sides q⁵ and the doctor q⁶ and will rest directly upon the passive surface of the apron or upon that portion of said apron which for the time being happens to be between the sides of the trough.

Motion imparted to the driving roller of the apron to occasion its rotation in the direction of the arrows in Figs. 1 and 8, will, as is obvious,—the apron being stretched taut between the two rollers under a tension determinable by the roller bolts p⁴,—cause the travel of the apron downwardly through the trough and beneath the edge of the doctor which is set to bear upon the breast of the driving roll; and the said apron in its travel from beneath the doctor will carry out from the trough, evenly spread, or “brushed,” so to speak, across its surface, such sufficient quantity of the paint as the set of the doctor will permit to escape, and the paint coated apron as to its active surface, or that portion of it which for the time being presents beneath the pad, will be a color-supplying device adapted to evenly, smoothly, and equally apply the paint to the entire face of the printing block pressed against it.

In the operation of the machine, a suitable amount of the desired paint, or other liquid coloring matter, is applied within each trough; and the troughs, as is apparent, can be readily cleaned to receive paints of different color, the apron itself being readily scraped free of any particular paint by adjusting the set of the doctor to accomplish such result.

The color-feed apron actuating devices.—All of the aprons are, as stated, intended to be intermittently and simultaneously advanced in order to present a fresh coated surface to their printing blocks each time the latter are elevated against them. The means by which this intermittent advance of the aprons may be occasioned is not of importance, and many devices can be employed for the purpose. I

have found a suitable contrivance to be the following, which I describe with reference to a single apron and as a single device, although it is repeated with each apron of the series 5 and is illustrated as double:—

Referring now especially to Figs. 1, 2, 3, 4, 5, 8, 9, and 15,—one of the gudgeons p^2 of the driving apron roller is prolonged beyond its box p^3 and provided with a fixed sprocket 10 wheel j over which passes an endless sprocket chain J which, as shown in Figs. 1 and 2, passes also over and is engaged with an upper idler sprocket wheel j' bracketed off from the upper part of the slotted standard, and a lower 15 idler sprocket wheel j'' bracketed off from the side frame in line below the upper sprocket wheel j' . The sprocket chain passing over these three sprocket wheels traverses a path which will be understood by a reference to 20 Fig. 1, and is as to a portion of said path parallel with and adjacent to the vertical slot in the standard. It is apparent that motion imparted to said sprocket chain in the direction of the arrows applied to it in Fig. 1, will occasion 25 the rotation of the apron driving roller with which it is connected in the direction of the arrows applied to said roller in Figs. 1 and 8, or in that direction which is necessary to advance the apron from out the trough across the face 30 of the pad. The device which I employ for occasioning this movement of the chain is a chain pawl j^3 mounted upon or suitably connected with the adjacent block-carrier coupling l , and controlled by a pawl spring j^4 , as 35 shown in Fig. 15. As the carrier pitman under consideration by reason of the throw of its platen crank is caused to ascend the chain pawl engages the sprocket chain and occasions such movement of said chain as will cause the 40 necessary advance of the apron. The descent of the carrier pitman is without effect upon said sprocket chain as the pawl slips loosely over it elevating its springs. The chains are shown as doubled, two being applied to each 45 apron driving roller one upon each side. It will, therefore, from a consideration of the movement of the carrier cranks, be apparent that the apron is advanced during the period when its block carrier is in the throw of its 50 cranks ascending, and that it is stationary during the period of the descent of said block carrier and until after it leaves the surface of the apron.

Such being a description of the color-feed 55 which I prefer to employ, it is apparent that the angle at which the apron is set—so long as it is sufficient to afford, as stated, in connection with the doctor and the sides q^5 a trough to contain liquid,—is not material, and that it 60 is simply necessary to adjust the stroke of the carrier pitmen in such manner that they will cause at the moment they complete their ascent a firm pressure of their printing blocks against the under face of the color supplied 65 apron upon the elastic bed.

In conclusion it is proper for me to state

that it is immaterial by what specific mechanical means the tumbling, oscillation, partial rotation, or reversal of the block carriers be occasioned, it being simply essential that they 70 should be tumbled, partly oscillated or partly rotated, or reversed, both in their ascent and descent; that it is immaterial in what manner the mechanism for occasioning their ascent and descent be applied to said block carriers, 75 although the construction which I have represented is that which I prefer; that as stated it is possible to operate the machine with a feed adapted to grip but one edge of the fabric, although it is preferable that the feed should 80 act upon both edges; that, as stated, it is preferable to apply some such arresting devices as the toe cams to the feed end of the bed as well as to the delivery end, in order to guard against the possible retreat of the fabric upon 85 the bed before it reaches the delivery end of said bed; and that other changes in mechanical detail especially as relating to the block-carrier actuating devices, the feed-operating devices, and the color apron operating devices 90 can obviously be resorted to without departure from the invention.

In Fig. 18 I have represented a modified form of block-carrier which is provided with tumbler plates k^5 of considerable depth and 95 weight, each of which is provided with a single curved tumbler pin way k^4 which is in continuous engagement with a single tumbler pin k^5 projecting from the slotted standard. This block-carrier is hung upon and turns with respect to carrier pivot pins k^x as in the case of the carriers first described, but receives its movement of tumbling or reversal through the action of the two single tumbler pins in engagement with its curved pin ways. In the 105 drawings the tumbler plate nearest the eye, which is drawn in full lines, is represented in the position which it occupies when the carrier is down upon the bed, while it is also represented in dotted lines with the carrier up 110 against the color apron. In the operation of this tumbling platen the weight of the prolonged or extended tumbler plates, or more strictly speaking, of that portion of said plates which is most remote from the carrier and beyond the pivot pins causes said plates to serve 115 as a counterbalance to assist in the tumbling or reversal of the carrier. I simply instance the foregoing construction as one of many possible modifications, any one of which will equally 120 serve to secure the reversal or tumbling of the block-carriers.

In Figs. 18 and 19 I have also illustrated a modified contrivance for operating the color aprons, and which I describe with reference to 125 a single apron, although it is to be represented with each apron of the series:—One of the gudgeons p^2 of the driving apron roller is prolonged beyond its box p^3 , and provided with a fixed ratchet faced clutch collar r , and also 130 provided with a sliding ratchet faced clutch sleeve r^x the ratchet face of which is the re-

verse counterpart of that of the fixed clutch collar. Intermediate between the ratchet faced clutch sleeve and the box of the gudgeon, is interposed a sleeve spring r^2 , conveniently 5 encircling the gudgeon, and serving normally to maintain the clutch faces of the collar and sleeve in contact.

R is a clutch-actuating strap one extremity of which is conveniently secured to the wrist 10 pin m of one of the carrier cranks of the block carrier in connection with which the apron under consideration operates, the other extremity of which is connected with a strap spring S connected with the frame-work, and 15 the intermediate portion of which is wrapped once or twice about the clutch sleeve so as to frictionally embrace the latter and occasion its rotation as the strap is drawn in either direction.

20 The operation will be readily understood: Assuming the carrier cranks to which the strap is secured at the top of its throw,—the descent of said crank to its lowermost position will occasion such draft upon the strap as will 25 rotate the clutch sleeve in engagement with its collar, and consequently rotate the apron driving roller in the direction of the arrow in Fig. 6, or that direction which is necessary to advance the apron from out the trough across 30 the face of the pad. The subsequent movement of the carrier crank from its lowermost to its uppermost position and the consequent slackening of the strap, will then permit the strap spring to take up the slack of the strap, 35 and occasion the free rotation of the clutch sleeve against the clutch collar, the respective ratchet faces of said sleeve and collar being so formed as to slip over each other during such action. It will therefore, from a consideration 40 of the movement of the carrier crank, be apparent that the apron is advanced during the period when its platen is, in the throw of its cranks, descending, and that it is stationary during the period of the ascent of said platen, 45 and until after it leaves the surface of the apron.

Having thus described my invention, I claim and desire to secure by Letters Patent of the United States:—

50 1. In an oil cloth printing machine, the following elements in combination:—first, a bed upon which the fabric to be printed is laid and along which it is caused to travel;—second, an intermittently operating fabric-feed which acts upon the fabric to occasion its intermittent predetermined advance;—third, a series of reciprocating reversing printing-block-carriers, which alternately simultaneously descend upon the fabric to print it and 55 simultaneously ascend against color-feeds; and, fourth, a series of color-feeds which supply color to the printing faces of the block-carriers; substantially as set forth.

2. In an oil-cloth printing machine, the following elements in combination:—first, a bed upon which the fabric to be printed is laid

and along which it is caused to travel; second, an intermittently operating fabric-feed which acts upon the fabric to occasion its intermittent predetermined advance; third, fabric-feed-operating devices which occasion the advance and retreat of the fabric-feed; fourth, a series of reciprocating reversing printing block carriers, which alternately simultaneously descend upon the fabric to print it and simultaneously ascend against the color-feeds; fifth, block-carrier-actuating devices which alternately occasion the simultaneous descent and the simultaneous ascent of the block carriers; and, sixth, a series of color-feeds which supply color to the printing faces of the block-carriers; substantially as set forth. 70 75 80

3. In an oil cloth printing machine, the following elements in combination:—first, a bed upon which the fabric to be printed is laid and along which it is caused to travel; second, an intermittently operating fabric-feed which acts upon both edges of the fabric to occasion its intermittent advance, and which is composed of two pairs of connected parallel feed bars; 85 third, a series of reciprocating reversing printing block carriers, which alternately simultaneously descend upon the fabric to print it and simultaneously ascend against color-feeds; and, fourth, a series of color-feeds which supply color to the printing faces of the block carriers; substantially as set forth. 90 95

4. In an oil cloth printing machine, the following elements in combination:—first, a bed upon which the fabric to be printed is laid and along which it is caused to travel; second, an intermittently operating fabric-feed which acts upon the fabric to occasion its intermittent predetermined advance; third, a series of reciprocating reversing printing block carriers, which alternately simultaneously descend upon the fabric to print it and simultaneously ascend against color-feeds; fourth, a series of color-feeds which supply color to the printing faces of the block carriers, and are 100 each composed essentially of an endless apron 105 operating in connection with a color trough; substantially as set forth. 110

5. In an oil cloth printing machine, the following elements in combination:—first, a bed upon which the fabric to be printed is laid and along which it is caused to travel; second, an intermittently operating fabric-feed which acts upon both edges of the fabric to occasion its intermittent advance, and which is composed of two pairs of connected parallel feed bars; 115 third, a series of reciprocating reversing printing block carriers, which alternately simultaneously descend upon the fabric to print it and simultaneously ascend against color-feeds; and, fourth, a series of color-feeds which supply color to the printing faces of the block carriers, and are each composed essentially of an endless apron 120 operating in connection with a color trough; substantially as set forth. 125 130

6. In an oil cloth printing machine, the fol-

lowing elements in combination: first, a bed upon which the fabric to be printed is laid and along which it is caused to travel; second, an intermittently operating fabric-feed which acts 5 upon both edges of the fabric to occasion its intermittent advance, and which is composed of two pairs of connected parallel feed bars; third, fabric-feed-operating devices which occasion the advance and retreat of the fabric-feed; fourth, a series of reciprocating reversing printing block carriers, which alternately simultaneously descend upon the fabric to print it and simultaneously ascend against color-feeds; fifth, block-carrier-actuating devices 15 which alternately occasion the simultaneous descent and the simultaneous ascent of the block carriers; and, sixth, a series of color-feeds which supply color to the printing faces of the block carriers, and are each composed essentially of an endless apron operating in connection with a color trough; substantially as set forth.

7. In an oil cloth printing machine, the following elements in combination: first, a bed upon which the fabric to be printed is laid and along which it is caused to travel; second, an intermittently operating fabric-feed which acts 25 upon both edges of the fabric to occasion its intermittent advance, and which is composed of two pairs of connected parallel feed bars; third, fabric-feed-operating devices which occasion the advance and retreat of the fabric-feed; fourth, a series of reciprocating reversing printing block carriers, which alternately simultaneously descend upon the fabric to print it and simultaneously ascend against color-feeds; fifth, block-carrier-actuating devices 30 which alternately occasion the simultaneous descent and the simultaneous ascent of the block carriers; sixth, color-feeds which supply color to the printing faces of the block carriers, and are each composed essentially of an endless apron operating in connection with a color trough; and, seventh, apron-operating devices which occasion the intermittent advance of the apron with respect to the color trough; substantially as set forth.

8. In an oil cloth printing machine, the following elements in combination:—first, a bed 40 upon which the fabric to be printed is laid and along which it is caused to travel; second, an intermittently operating fabric-feed which acts upon both edges of the fabric to occasion its intermittent advance, and which is composed of two pairs of connected parallel feed bars; third, oscillatory levers which occasion the 45 advance and retreat of the feed bars; fourth, a series of reciprocating reversing printing block carriers, which alternately simultaneously descend upon the fabric to print it and simultaneously ascend against color-feeds; fifth, cranks and pitmen which occasion the alternate ascent and descent of the block carriers; sixth, a series of color-feeds which supply color to the printing faces of the block 55 carriers, and are each composed essentially of

an endless apron operating in connection with a color trough; seventh, apron-operating devices which occasion the intermittent advance of the apron with respect to the color trough; 70 and, eighth, means, essentially, for instance, such as set forth, for occasioning the concomitant action of the feed levers, the carrier cranks and pitmen, and the apron-operating devices; substantially as set forth. 75

9. In an oil cloth printing machine, the following elements in combination:—first, a bed upon which the fabric to be printed is laid and along which it is caused to travel; second, an intermittently operating fabric-feed which acts 80 upon the fabric to occasion its intermittent predetermined advance; third, a series of reciprocating reversing printing block carriers, which alternately simultaneously descend upon the fabric to print it and simultaneously 85 ascend against color-feeds; fourth, a series of color-feeds which supply color to the printing faces of the block carriers; and, fifth, a tension roller; substantially as and for the purposes set forth. 90

10. In an oil cloth printing machine, the following elements in combination:—first, a bed upon which the fabric to be printed is laid and along which it is caused to travel; second, an intermittently operating fabric-feed which 95 acts upon the fabric to occasion its intermittent predetermined advance; third, a series of reciprocating reversing printing block carriers, which alternately simultaneously descend upon the fabric to print it and simultaneously 100 ascend against color-feeds; fourth, color-feeds which supply color to the printing faces of the block-carriers; and, fifth, arresting devices, essentially such as the toe cams, to prevent the accidental retreat of the fabric after its 105 advance; substantially such as set forth.

11. A fabric-feed device for an oil cloth printing machine, which acts upon the edges of the fabric to be printed, and is composed essentially of two pairs of link-connected 110 parallel bars, substantially as set forth.

12. In an oil cloth printing machine, the following elements in combination:—first, a bed upon which the fabric to be printed is laid and along which it is caused to travel; second, 115 ways formed in or applied to said bed; third, two pairs of link-connected parallel bars, one of the bars of each of which pair is adapted to travel in the aforesaid ways; fourth, means, essentially such as the feed levers, which occasion the intermittent reciprocation of the feed bars; and, fifth, means, essentially such as the feed cam, for occasioning the operation of the feed levers; substantially as set forth. 120

13. In combination with the feed bars,—the lever housings provided each with a reversing face, a draft face, and an idle face,—the oscillatory feed levers,—and means, essentially such as set forth, for operating said levers, substantially as set forth. 125

14. A color-supplying-device or color-feed for the printing block of an oil cloth printing

machine, which is composed, essentially, of an endless traveling apron with reference to which is mounted or superimposed a color trough, with respect to which it, the said apron, travels, substantially as set forth.

15. A color-supplying-device or color-feed for the printing block of an oil cloth printing machine, which is composed, essentially, of an endless traveling apron with reference to 10 which is mounted or superimposed a color trough with respect to which it, the said apron, travels, and which is also provided with a cushioned, elastic, or resilient surface with respect to which it also travels, substantially 15 as set forth.

16. A color-supplying-device or color-feed for the printing block of an oil-cloth printing machine, which is composed, essentially, of an endless traveling apron with reference to 20 which is mounted or superimposed a color trough with respect to which it, the said apron, travels,—which is also provided with a cushioned, elastic or resilient surface with respect to which it also travels,—and which is also 25 provided with a doctor to remove surplus color from it the said apron, substantially as set forth.

17. A color-supplying-device or color-feed for the printing block of an oil cloth printing 30 machine, which is composed, essentially, of an endless traveling apron with reference to which is mounted or superimposed a color trough with respect to which it, the said apron, travels,—which is also provided with a cushioned, elastic, or resilient surface with respect 35 to which it also travels,—and which is also provided with a doctor to remove surplus color from it the said apron,—in combination with means, essentially such as set forth, which occasion 40 the intermittent travel of the apron with respect to the trough, elastic surface, and doctor, substantially as set forth.

18. A color-supplying device or color-feed for the printing block of an oil cloth printing machine, which is composed essentially of an 45 endless traveling apron which as to its active face travels over a cushioned, elastic, or resilient surface, and which as to its passive surface travels through a color trough provided with a doctor to remove surplus color from it 50 the said apron; in combination with means, essentially such as set forth, which occasion the intermittent travel of the apron with respect to the trough; with a reciprocating reversing printing block carrier; with a bed 55 upon which the fabric to be printed is laid and along which it is caused to travel; and with an intermittently operating fabric feed which acts upon the fabric to occasion its intermittent predetermined advance upon said bed; substantially as set forth.

19. The combination to form a color-supplying device or color feed; of an endless traveling apron; a pair of rollers over which said apron travels; adjustable boxes with respect 65 to which the rollers are journaled; a cushion, pad, or other elastic or resilient surface, over which the active face of the apron travels; a frame-work for supporting said pad and the adjustable boxes of the rollers; a trough combined with said frame work, through which the passive surface of the apron travels and the floor of which trough is composed of said passive surface of said apron; and an adjustable doctor which serves to remove surplus 75 color from the apron after its passage through said trough, substantially as set forth.

In testimony whereof I have hereunto signed my name this 18th day of April, A. D. 1887.

NELSON LEWIS TUCK.

In presence of—

J. BONSALL TAYLOR,
WM. C. STRAWBRIDGE.
